UNITED STATES PATENT OFFICE.

EDWARD N. JACOBI, OF MILWAUKEE, WISCONSIN, ASSIGNOR TO BRIGGS & STRATTON CORPORATION, OF MILWAUKEE, WISCONSIN, A CORPORATION OF WISCONSIN.

SWITCH CONSTRUCTION.

Application filed April 13, 1927. Serial No. 183,460.

This invention relates to certain new and useful improvements in switch construction and refers more particularly to a switch of the type most commonly utilized on automotive vehicles.

In switches of the character described, it is frequently customary to provide mounting means on the outer face of the switch terminal carrying head for incorporating a fuse in one of the switch circuits, most frequently the lighting circuit. Heretofore, it has been customary to mount the fuse between a pair of spring clips one of which is fixed close to the terminal carrying head 10 in electrical engagement with one terminal and the other of which is fixed on the outer end of a bracket member secured to the head in electrical engagement with another terminal, the bracket arm being mounted by a 15 brass bushing, forming a terminal and adapted to enter an aperture in the bracket member to be riveted thereover.

This construction is objectionable in that it requires a brass bushing, the operation of 25 inserting the same in place and an electrical connection between the bushing and the fuse bracket, and this invention has as an object the provision of an improved switch fuse mounting bracket construction wherein the 30 terminal is integral with the bracket to eliminate the brass bushing, the labor cost of inserting the same and the necessity of an electrical joint between the bracket and the terminal.

Another object of this invention resides 35 in the provision of an improved switch construction of the character described in which the fuse carrying bracket has a tongue projection adapted to be extended through an 40 opening in the terminal carrying head and clinched thereover to mount the bracket and form a contact terminal.

And a still further object of this invention resides in the provision of an improved 45 fuse mounting bracket for a switch device which is formed in one piece, is capable of easy attachment to the terminal carrying head, effects an economy in construction by eliminating one part and the labor cost of 50 inserting the same and which is more efficient as it eliminates one electrical joint.

With the above and other objects in view 55 which will appear as the description proceeds, my invention resides in the novel construction, combination and arrangement of

parts substantially as hereinafter described and more particularly defined by the appended claims, it being understood that such changes in the precise embodiment of the herein disclosed invention may be made as 60 come within the scope of the claims.

In the accompanying drawing, I have illustrated one complete example of the physical embodiment of my invention constructed according to the best mode I have so far 65 devised for the practical application of the principles thereof, and in which:

Figure 1 is an elevational view of the back of a portion of an automotive vehicle dash board or instrument panel illustrating my 70 improved device applied thereto;

Figure 2 is a view, partly in section and partly in elevation, taken through Figure 1 on the plane of the line 2-2;

Figure 3 is a perspective view illustrating 75 in detail the construction of the terminal carrying head and fuse mounting bracket carried thereby, and

Figure 4 is a detail view of the blank from 80 which the improved bracket member is formed.

Referring now more particularly to the accompanying drawing, in which like numerals designate like parts throughout the several views, 5 designates a switch casing 85 adapted to be suitably mounted on the dash board or instrument panel 6 of an automotive vehicle. An escutcheon or mounting plate 7 surrounds the switch which consists of suitable mechanism for controlling, in the 90 present instance, the ignition and the lighting circuits of an automotive vehicle.

The lighting circuit of the switch consists of a driver member 8 controlled by a suitable operating lever 9 and rotating with 95 in the casing 5 in the conventional manner. Driving lugs 10 carried by the driver member project into the casing through arcuate slots therein and are drivingly connected with a fibre disc 11 controlling a contact carrier 12 having spring contact fingers 13 electrically connected therewith for engagement with terminals 14 mounted on a terminal carrying head 15. The head 15 closes the inner end of the casing 5 and the wires 105 of the circuit in which the terminals 14 are included are suitably connected to the terminals at the rear of the head. As will be readily apparent, rotation of the lever 9 engages the spring contact fingers 13 with sets 110

of terminals 14 to close the various circuits of the lighting system.

The ignition or other circuit is operated independently of the lighting circuit through a key actuated tumbler 16 having an elongated driving lug 17 extended into the casting for driving engagement with a fiber disc 18 carrying a contact 19 having two spring contact fingers 20 and 21 adapted for engagement with terminals 22 and 23, terminal 22 being centrally disposed with respect to the head 15 and in constant electrical engagement with the spring contact finger 20, and the finger 21 being selectively engageable with the terminals 23.

The foregoing switch construction is a conventional type and it is to be understood that my invention, now about to be described, may be used in connection with any type of switch whether solely ignition or lighting circuit or a combination of both as illustrated, and pertains especially to the improved means for mounting a fuse 24 in one of the circuits, the present embodiment illustrating its incorporation in the lighting circuit. The fuse 24 is preferably of the cartridge type and has its inner end engageable with a spring contact clip 25 in electrical engagement with one or more of the terminals 14 and its outer end engaged with a spring contact clip 26 carried by the outer end of a bracket member 27.

The bracket member is stamped from a one-piece blank, as illustrated in Figure 4, and has an elongated tongue portion 28 at its inner end with a pair of lateral lugs 29 spaced inwardly thereof, the tongue and lugs being bent, as illustrated in Figure 2, to form a base portion 30 engaging the outer or rear face of the terminal carrying head 15 with its end 31 extended through a slot 32 therein which is clinched thereover, as at 33, to secure the bracket member to the head 15, the clinched portion of the lug 28 forming the terminal 22 and having a depression therein to receive the end of the spring contact finger 20. The lugs 29 are formed on the vertical portion of the bracket member at its juncture with the portion 30 and are twisted approximately ninety degrees to form side flanges and extend through slots 35 in the head 15, being clinched over the head to, with the tongue 28, rigidly mount the bracket member. The forming of the lugs 29 at acute angles with respect to the tongue 28 provides a substantially channel shaped base portion for the bracket member proper to give added rigidity, as will be readily apparent.

From the foregoing description taken in connection with the accompanying drawing, it will be readily apparent to those skilled in the art to which an invention of the character described appertains that I provide a novel and improved fuse mounting bracket

member which is constructed in one piece to effect an economy in material and assembling cost, which is more effective in operation in that the necessity of an electrical joint between the terminal 22 and the fuse 24 mounting bracket is eliminated and which is of very strong and durable structure.

What I claim as my invention is:

1. In a switch construction, a terminal carrying head having a pair of spaced substantially parallel slots therein and another slot disposed transversely with respect to the first slots, a bracket member adapted to be mounted on the terminal carrying head, a tongue portion carried by the bracket member and extended through the last-mentioned slot and folded over the terminal carrying head to clamp the bracket member in place, and lugs carried by the bracket member and extended into the first-mentioned slots of the terminal carrying head. 75

2. In a switch construction, a terminal carrying head having a pair of parallel spaced slots and a transverse slot, a bracket member, a laterally extended base portion at the inner end of the bracket member adapted to engage the outer surface of the terminal carrying head, a tongue extended from the bracket member and passed through the terminal carrying head transverse slot and clinched over the head to secure the bracket member in place, the clinched portion of said tongue forming a terminal, and lugs carried by the bracket member and extending into the first slots of the terminal carrying head. 90

3. In a switch construction, a terminal carrying head having a pair of parallel spaced slots and a transverse slot, a bracket member, a laterally extended base portion at the inner end of the bracket member adapted to engage the outer surface of the terminal carrying head, a tongue portion extended from the bracket member and passed through the terminal carrying head slot and clinched over the head to secure the bracket member in place, said tongue portion forming a terminal, and lugs carried by the bracket member and extending into the first slots of the terminal carrying head, said lugs being clinched over the inner surface of the terminal carrying head to assist the tongue portion in rigidly mounting the bracket member on said head. 105

4. In a switch construction, a terminal carrying head having a pair of parallel spaced slots and a transverse slot, a bracket member, a laterally extended base portion at the inner end of the bracket member adapted to engage the outer surface of the terminal carrying head, a tongue portion extended from the bracket member and passed through the terminal carrying head slot and clinched over the head to secure the bracket member in place, said tongue 115 120 125 130

- portion forming a terminal, lugs carried by the bracket member and extended into the first slots of the terminal carrying head, said lugs being clinched over the inner surface of the terminal carrying head to assist the tongue portion in rigidly mounting the bracket member on said head, and means for electrically connecting a conductor with the bracket member.
- 5 10. 5. In a switch construction, a terminal carrying head, a bracket member, a laterally extended base portion at the inner end of the bracket member adapted to engage the outer surface of the terminal carrying head,
- 15 15. a tongue portion extended from the bracket member and passed through the terminal carrying head and clinched thereover to secure the bracket member in place, said tongue portion forming a terminal, lugs
- 20 20. carried by the bracket member and extended through the terminal carrying head and clinched thereover to assist the tongue portion in rigidly mounting the bracket member on said head, means for electrically connecting the conductor with the bracket member,
- 25 25. a fuse clip fixed to the terminal carrying head adjacent the base of the bracket member, and a second clip carried by the outer end portion of the bracket member.
- 30 30. 6. In a switch construction including an enclosing case, a terminal carrying head enclosing the case and having a pair of spaced,
- substantially parallel slots therein and another slot disposed transversely with respect to the first slots and switch instrumentalities mounted within the case and including a movable contact, a terminal member adapted to be mounted on the terminal carrying head, a tongue portion carried by the terminal member and extended through the last-mentioned slot and folded over the terminal carrying head to secure the terminal member in place, and lugs carried by the terminal member and extended into the first-mentioned slots of the terminal carrying head.
- 35 7. In a switch construction, a terminal carrying head of insulating material, a curved segmental strip disposed concentrically on one face of the terminal carrying head to provide an elongated contact, a metal bushing secured to one end of the segmental strip and passed through the terminal head to present a tapped terminal screw receiving hole to the other face of the terminal head, and the other end of the segmental strip being passed through an opening in the terminal head and clinched thereover whereby said elongated contact is secured to the terminal head at both ends.
- 40 45 50 55 60

In testimony whereof I hereunto affix my signature.

EDWARD N. JACOBI.
